UNITED STATES PATENT OFFICE.

CASPER F. LOCHNER, OF JEFFERSON, ASSIGNOR, BY MESNE ASSIGNMENTS,
TO FRANK STERNE, OF HOUSTON, TEXAS.

SPARK-ARRESTER.

SPECIFICATION forming part of Reissued Letters Patent No. 10,093, dated April 25, 1882.

Original No. 217,542, dated July 15, 1879. Application for reissue filed February 8, 1882.

To all whom it may concern:

Be it known that I, CASPER F. LOCHNER, of Jefferson, Marion county, Texas, have invented certain new and useful Improvements in Spark-
5 Arresters, of which the following is a specification.

The object of my invention is to provide a simple and effective device capable of arresting sparks and returning them to the smoke-
10 arch of a locomotive-chimney, and without in the least interfering with the free and unob-
structed escape of smoke. This result is ac-
complished by fitting within the chimney a se-
ries of flanges or wings that curve outwardly
15 from a common center toward the shell of the
stack or chimney, a deflecting-plate being lo-
cated above these curved wings or flanges for
the purpose of preventing the smoke taking
20 a direct central passage through the chimney,
as hereinafter more fully described.

In the annexed drawings, Figure 1 is an axial section of my improved spark-arrester. Fig. 2 is a plan of the curved wings and de-
25 deflecting-plate detached from the smoke-stack. Fig. 3 is a side elevation of said wings and plate.

A represents the base, and B the custom-
ary flaring portion of an ordinary locomotive
30 chimney or smoke-stack. Secured to the base
A are standards C, that support a deflecting-
plate, E, of somewhat less diameter than the
chimney, so as to afford an annular passage, F,
35 for the escape of smoke and the other gaseous
products of combustion. Arranged under this
deflecting-plate are the curved wings or flanges
G, radiating or proceeding from a common
center in line with the axis of the smoke-stack,
40 the shape of said wings being more clearly
shown in Fig. 2. The lower margins of said
wings are attached to a hoop, I, which hoop
or ring is of the same diameter as that portion
45 of the chimney with which it is in contact.
Located above the plate E is a perforated cyl-
inder, J, secured within the mouth or ventage
K of the smoke-stack.

The operation of the above-described ar-
rangement of devices is as follows: When the
products of combustion are driven upwardly
50 through the chimney A by the blast of the en-
gine the sparks are arrested by the plate E,
which deflects them laterally and prevents

them escaping directly from the stack. This lateral deflection of the sparks causes them to traverse the various spaces or chambers be-
55 tween the curved flanges or wings G, by which means a whirling motion is imparted to said sparks. This whirling motion throws them outwardly against the shell B, from whence they fall back into the smoke-arch in an ex-
tinguished condition, that allows them to be 60 removed whenever desired. In the meantime the smoke and other gaseous products of com-
bustion are free to escape through the annular space F into the perforated cylinder J, and thence out at the upper open end of the 65 latter.

As the various wings or flanges G curve out-
wardly from a common vertical center coin-
cident with the axis of the smoke-stack, it is
evident the products of combustion have the
70 above-described whirling motion imparted to
them as soon as they ascend far enough with-
in the chimney to enter the numerous spaces
or channels between these curved wings. This
result could not be obtained if the inner ends
75 of the flanges were not in direct contact with
each other, as the least separation of said ends
would afford a common central opening com-
municating with all the spaces or channels be-
tween said flanges, and affording room for the
80 products of combustion to "chamber" in, and
thereby prevent their prompt lateral dispersion.
Furthermore, spark-arresters composed
of curved wings having their intervening chan-
nels in communication with a common central
85 opening or chamber are admitted to be old,
and therefore my claims are not to be con-
strued as an attempt to cover such devices.

I claim as my invention—

1. A spark-arrester consisting of a series of 90 curved wings or flanges, G, surmounted with a deflecting-plate, E, the inner ends of said flanges being united at or near the axis of the stack, so as to avoid a common central opening or chamber communicating with the channels 95 between the flanges G, as herein described.

2. The combination, in a smoke-stack, of de-
flecting-plate E, perforated cylinder J, and a
series of wings or flanges, G, which latter curve
outwardly from a common center, as and for
the purpose described.

3. The combination, in a smoke-stack, of the

deflecting-plate E, provided with curved flanges or wings G, radiating from a common center, said plate being supported on the standards C, arranged as herein described.

5 4. The combination of shell A B, standards C, perforated cylinder J, and deflecting-plate E, which plate is provided with a series of curved wings or flanges, G, radiating from a common center, said perforated cylinder being

secured in the mouth K of the stack, as herein described.

In testimony whereof I affix my signature in presence of two witnesses.

CASPER F. LOCHNER.

Witnesses:

JOHN SPEED,

J. WM. REINHARDT.
